UNITED STATES PATENT OFFICE.

RICHARD H. MATHER, OF WINDSOR, CONNECTICUT.

DESIGN FOR A STEAM-ENGINE BED.

SPECIFICATION forming part of Design No. 19,923, dated June 24, 1890.

Application filed April 18, 1890. Serial No. 348,553. Term of patent 14 years.

To all whom it may concern:

Be it known that I, RICHARD H. MATHER, a citizen of the United States, residing at Windsor, in the county of Hartford and State of Connecticut, have invented and produced a new and original Design for Beds for Steam-Engines, of which the following is a specification, reference being had to the accompanying drawings, forming part thereof.

Figure 1 is a side elevation of the bed. Fig. 2 is a transverse section of the bed.

The invention relates to the shape or configuration of the bed or frame of horizontal steam-engines.

The leading feature of my design consists in the shape, the lines of which at the cylinder end of the bed are parallel, but which, back of the annular bead *b*, at the end of the cylinder *a*, expand outwardly in an unbroken line, an ogee curve swelling gradually from the cylinder to the crank, but rounding more quickly at the crank end. The forward end of the base-plate *c* rises vertically to the rear end of the cylinder, while the rear end of the base-plate curves forward, making junction with the rounded butt of the bed somewhat forward of the rear end of the bed.

This design of the shape of the bed, swelling from the cylinder to the crank end in unbroken lines, instantly produces in the mind of an observer a vivid impression of the solidity and strength of the bed, which character-

istics are essential to a successful engine-bed, while at the same time the lines are graceful, symmetrical, and pleasing, artistically as well as mechanically.

The smoothness of the rounded sides of the bed is relieved by a bead *d*, that extends in an unbroken loop, which is smaller at the cylinder end and swells outwardly to the butt relatively to the contour already described. As this bead extends in an unbroken loop, swelling relatively to the top contour of the bed, it gives the impression that the bottom line, which of course is broken by the base-plate, is swelled similarly to the top contour-line, producing the effect of a complete pear-shaped figure laid on its side.

I claim as my invention—

The herein-shown design for a horizontal steam-engine bed, the same having an unbroken contour gradually swelling from the cylinder end to the crank end and quickly curving around the crank, the smooth sides of which are relieved by a bead forming a continuous loop that is swelled at the butt relatively to the butt of the bed, a portion of one side of the bed having a plane surface.

RICHARD H. MATHER.
